(57) **CLAIM**

The ornamental design for a key organizer, as shown and described.

DESCRIPTION

FIG. 1 is a front perspective view of a key organizer according to the present invention.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof.

FIG. 7 is a bottom plan view thereof.

FIG. 8 is a front perspective view thereof in a folded or closed position; and,

FIG. 9 is a front perspective view of FIG. 1 in a partial unassembled state.

The dashed lines illustrate environment that does not form a part of the present invention, and no claim is made to the material illustrated with dashed lines.
